UNITED STATES PATENT OFFICE.

PETER STENGER, OF FORT WAYNE, INDIANA, ASSIGNOR TO DEISTER CONCENTRATOR COMPANY, OF FORT WAYNE, INDIANA, A CORPORATION.

ORE-CONCENTRATOR.

1,105,109.

Specification of Letters Patent.

Patented July 28, 1914.

Application filed December 1, 1913. Serial No. 804,071.

To all whom it may concern:

Be it known that I, PETER STENGER, a citizen of the United States, residing at Fort Wayne, in the county of Allen and State of Indiana, have invented new and useful Improvements in Ore-Concentrators, of which the following is a specification.

This invention relates to ore concentrators and particularly to that form of the same generally known as slime concentrators, in which a plurality of decks or tables are superimposed in a frame for treating slimes, particularly the slimes which are the overflow from settling tanks or the like, the purpose of the treatment being to separate from such slimes as much as possible of the valuable material which is thereafter treated on other forms of concentrating tables. The slime is fed simultaneously to all the decks and is permitted to run over the same and the materials which are of sufficient gravity to cling to the surface of the decks are washed off at intervals of time.

The object of this invention is to provide a concentrator of the class described with novel means for effectively washing off the several decks or tables at predetermined intervals of time.

In the drawings is illustrated the preferred manner of carrying out the invention in practice, in which—

Figure 1 is a side elevation of a concentrator constructed according to my invention; Fig. 2 is an end elevation; Fig. 3 is an enlarged fractional plan view; Fig. 4 is an enlarged detail of the washing devices; Fig. 5 is an elevation of the mechanism for operating the wash water valves; and Fig. 6 is a plan view of the same.

Referring to the drawings, in all the figures of which like reference numerals indicate like parts, the main frame consists of corner posts 1, end cross bars 2 and side bars 3. Suitably fixed to the frame in an inclined position are a suitable number of concentrating tables 4 which may be as wide as the main frame or they may be narrower than the frame and arranged in pairs. Each table has a wooden floor covered with suitable material such as canvas. At the upper end of each table is a feed distributing board 5 which delivers the slime pulp along the upper end of the table. Pulp is delivered through pipes 6^a to each distributing

board from a pulp box 6 conveniently arranged for the purpose. 55

A water main 7 is suitably supported in the upper part of the main frame and adjacent one side thereof. One end of the main is connected to a water supply system, the other end being closed. Valve casings 8 are connected to branch pipes 9 which are connected to main 7 at suitable distances apart. Each casing has within it a suitable valve the stem 10 of which projects upwardly from casing 8. The upper end of the stem is pivoted to a lever 11, one end of which lever is provided with a roller 12 and the other end of which is provided with a suitable counterweight 13. 70

To the lower end of each valve casing 8 is connected a pipe 14 which extends downwardly adjacent the sides of the several tables. The lower end of each pipe is closed. A series of pipes 15 is connected at one end 75 to each pipe 14 and extends transversely across the table or tables, one pipe of each series for each table or pair of tables. The other ends of pipes 15 are closed and are suitably supported in a bar or bracket 16 which is secured to the main frame. Each pipe 15 is provided with a suitable number of discharge nozzles 17 which are so arranged on the pipe as to discharge water onto the decks beneath them in the same direction as the direction of flow of the slime, that is, toward the foot of the table. The nozzles 17 are of such form as to spread the water in a fan-like film over the deck of the table beneath it. This film of water strikes 85 the surface of the table with considerable force and washes the materials down the slope of the table. The first series of nozzles washes the materials toward and to the second series; the second series of nozzles 90 drives them to the third series and so on down the slope until the materials are finally washed off the tables at the lower end.

The valves in casings 8 are opened in succession by the devices about to be described, 100 the valve nearest the upper end of the tables being opened first, then each one in succession thereafter.

The valve operating mechanism is as follows: A shaft 18 is revolvably mounted on 105 the main frame and is provided with a series of cam wheels or rollers 19 which are secured to it, one cam above each lever 11,

the roller 12 on the corresponding lever being in contact with the periphery of the cam. The cams are arranged on the shaft so that when the eccentric portion of one cam is in contact with the roller of the corresponding lever it will actuate said lever to raise the connected valve and permit water to flow from main 7 and branch pipe 9 into the pipe 14 and pipes 15 which said valve controls, while all the other valves remain on their seats. The preferred arrangement of cams is such that the one nearest the feed end of the tables will open its valve first. As the roller 12 leaves the eccentric portion of said cam the counterweight 13 on the end of the lever causes the lever to rock in the opposite direction and to close the valve. At this moment the second cam opens the second valve; then the third cam opens the third valve as the second valve is closed, then the fourth cam opens the fourth valve as the third valve is closed. The intent is that shaft 18 shall be operated at certain intervals of time and then given one or more revolutions. The further intent is that the slime shall be permitted to flow over the several decks for a predetermined period of time without any wash water being delivered onto the decks. During this period of time the mineral values and heavier sands will tend to settle to the surface of the decks and to cling thereto. When the allotted period of time has expired the cam shaft is put into motion and the wash water washes off the materials which have clung to the deck surfaces.

At the foot of the tables is provided a tilting board 20 upon which the materials from all the tables fall as they leave the latter. In practice the board is tilted with its outer edge down while the slimes are fed onto the tables without wash water so that the tailings will pass beyond the end of the device. When the wash water is applied to the decks board 20 is tilted in the opposite direction so that the materials washed off the decks will pass into a suitable receptacle and be saved for future treatment. This tilting effect is produced by a cam 21 fixed on shaft 18 upon the periphery of which rides a roller 22 carried by lever 23, which lever is pivotally connected to a rod 24, the rod being also pivotally connected to a rod 25 which is secured to board 20 in such manner that while roller 22 is in contact with the concentric portion of the cam the board will be tilted on its pivotal pins 26 to receive and discharge the washed materials. When the roller drops into the eccentric portion of the cam the board drops in the opposite direction and remains in such position until the cam again tilts it. The cam is necessarily rotated a complete turn and is then at rest since it is secured to shaft 18 which is driven a complete revolution at predetermined intervals.

While the wash water is being applied to the decks the supply of pulp may or may not be cut off. It is not necessary to cut off the supply of pulp as the decks readily take care of the feed of pulp whether they are being washed off or not.

In order that the cam shaft shall be automatic in its operation I have provided a clutch and timing mechanism in connection with it which is illustrated particularly in Figs. 5 and 6, and is described as follows:

A gear 27 is loosely mounted on shaft 18 and is provided on one face with a concentric boss 28 which has notches or recesses 29 in its forward face. This notched boss forms one member of a clutch. The other member 30 of the clutch is slidably secured to the shaft and is provided with tongues adapted to engage in the notches 29 when they are in apposition. A lever 31 is pivoted at one end to a suitable part of the main frame, as bracket 35, and to clutch member 30. A suitable spring 32 is connected to the free end of lever 31 and to the main frame and tends to draw member 30 into contact with boss 28. Member 30 is provided with a peripheral groove 33 into which a bar 34 is adapted to engage. Bar 34 is pivoted near one end to the main frame or to bracket 35 secured thereto, and the extremity is connected to a link 36 which link is also connected to lever 37 of the timing clutch operating device about to be described.

A worm 38 on a shaft 39 suitably mounted above gear 27 meshes with said gear and a pulley 40 on shaft 39 is driven by a belt leading to a suitable source of power. Gear 27 is therefore driven at all times.

A bar or plate 41 is mounted on the forward face of gear 27, it being secured to the gear by bolts 42 which pass through slots 43 in the plate so as to permit the plate to yield or have a slight oscillation on the gear. Springs 44 are connected to the plate and to the gear which tend to hold the plate in one position on the gear. A beveled lug 45 projects forwardly from plate 41 and is adapted to bear against the side edge of lever 31 or a projection 46 thereon, when the clutch members 28 and 30 are in engagement, for the purpose of forcing them apart when the locking bar 34 is withdrawn from groove 33 in clutch member 30 by the timing device.

The timing device consists of a suitably mounted gear 47 and on the inner surface of the rim of the gear a roller 48 on the inner end of lever 37 is adapted to roll. A cam 49 is provided at a suitable point on the rim over which the roller on lever 37 must travel and by which the lever is rocked to cause locking bar 34 to be disengaged from groove 33 in clutch member 30.

A worm 50 on shaft 51 meshes with gear 47. A gear 52 on shaft 51 is in mesh with a pinion 53 on shaft 54 and pulley 55 on

shaft 54 is connected by a belt to the source of power. Gear 47 is therefore continuously rotated and it and gears 52 and 53 and pulley 55 are so proportioned that the gear will 5 make one complete revolution during the period of time that it is desired to feed pulp to the decks without the deposit of wash water thereon. Of course gear 27 and its driving worm and pulley are likewise proportioned so that, when the clutch is thrown in, the gear will cause the cam shaft 18 to 10 make one or more revolutions before the clutch is thrown out.

When the clutch is thrown out by the 15 beveled lug 45 the lug forces clutch member 30 outwardly a sufficient distance to permit the locking bar 34 to drop into groove 33, this movement of bar 34 being accomplished by weight 56 which is attached to the free 20 end of said bar.

The operation of the device is apparent from the foregoing description. Briefly stated, it is as follows: The pulp is turned on all the tables simultaneously and the 25 power is connected to pulleys 40 and 55, the cam surface on gear 47 of the timing device being in advance of the end of lever 37. The clutch members are therefore disconnected and gear 27 is running idly, and gear 47 is 30 rotating. When the cam surface of gear 47 meets the roller on the end of lever 37 the lever is actuated to raise locking bar 34 thereby permitting spring 32 to connect the two portions of the clutch, the rotation of 35 gear 27 being so timed with respect to the rotation of gear 47 that the recesses in boss 28 on gear 27 are in coincidence with the lugs on member 30 at the moment the cam surface on gear 47 actuates lever 37. When 40 the clutch is thus thrown in, gear 27 is connected to the cam shaft 18 and said shaft is caused to rotate. The cams on this shaft cause the valves in casings 8 to open in succession as before described whereby the wash 45 water is discharged onto the several decks to wash off the materials. When the clutch is thrown in, beveled lug 45 on plate 41 has just passed lever 31. As lug 45 again reaches the same point in its travel it bears against 50 projection 46 on lever 31 disconnecting the clutch members, and locking bar 34, which has been riding on the surface of clutch member 30, drops into groove 33 as the groove is brought into register with the bar. 55 The cam shaft therefore stops and the pulp continues to flow without the wash water discharge until lever 37 is again actuated by the cam surface on gear 47.

I have found it desirable that the pulp 60 should be fed for several minutes, say ten minutes, between each operation of the valves.

Numerous modifications in details of construction and arrangement of the various 65 parts are obvious to one skilled in the art,

hence, I do not wish to be limited to the precise construction and arrangement shown and described.

Any number of decks may be used and any number of discharge nozzles or any number 70 of sets of nozzles may be used which may be arranged to discharge water onto the decks at selected points.

It will be noted that each branch pipe 14 with the pipes 15 connected thereto is substantially 75 a manifold through which water is passed to be discharged onto each deck simultaneously and at a selected point.

What I claim is:

1. In an ore concentrator having a plurality of decks, the combination of a plurality of manifolds for discharging water onto each deck at selected longitudinally separated points thereon, a water supply main having a connection with each manifold, means in each connection for controlling the flow of water therethrough, and means to operate the controlling means in succession and at predetermined intervals of time. 80

2. In an ore concentrator the combination with an inclined deck, of a plurality of fixed water distributors extending transversely of the deck and adapted to discharge wash water onto the deck at selected longitudinally spaced points, and automatically operated means to control the discharge of water from said distributors in succession at predetermined points of time. 95

3. In an ore concentrator the combination, 100 with an inclined deck, of a plurality of rows of discharge nozzles extending transversely of the table and adapted to discharge water onto the deck at selected longitudinally separated points, and automatically operated 105 means for controlling the discharge of water from said rows of nozzles independently at predetermined points of time, and in order of succession.

4. In an ore concentrator the combination 110 with an inclined table deck, of a series of rows of discharge nozzles arranged transversely of the deck and adapted to discharge water onto the deck at predetermined longitudinally separated points, valves to control 115 the supply of water to each row of nozzles and means to automatically operate the valves independently and at predetermined points of time, and in order of succession.

5. In an ore concentrator having a multiplicity of decks over which materials to be treated are adapted to be passed, the combination of a plurality of wash water means for each deck, each one of said means having a source of water supply in common 125 with one said means for each of the other decks, means to control the flow of water into said sources of water supply independently, means to actuate the controlling means in succession and at predetermined points of 130

- time whereby wash water is discharged onto each deck at a plurality of points in succession, the discharge being simultaneous on each deck at any one selected point.
6. In an ore concentrator having a plurality of inclined table decks, the combination of a plurality of nozzles for each deck arranged to discharge water onto the same at selected points thereon, means to control the supply of water to the nozzles, a cam shaft having independent connections to the latter means for operating the same, means to rotate the cam shaft, means to connect the latter means to the shaft at predetermined intervals of time and means to disconnect the same at predetermined intervals of time.
7. In an ore concentrator the combination with an inclined deck, of a plurality of means for discharging wash water onto the deck at selected points thereon, a water supply main having an independent connection to each of said means, a valve in each connection for controlling the supply of water to said means, a revolubly mounted cam shaft having connections with the valves for independently operating the same, means to drive the cam shaft, means to automatically connect the driving means to the shaft at predetermined points of time and means to disconnect the same at predetermined points of time.
8. In an ore concentrator the combination with a plurality of inclined decks, a water supply main common to all the decks, a series of means arranged above each deck and at selected points down the slopes thereof for discharging wash water onto the same, each member of each said series having a connection, in common with one member of each of the other series, with the supply main, valves to control the latter connections independently, a cam shaft operatively connected to the valves for operating the same successively and means operatively connected to the cam shaft for rotating the same at predetermined points of time.
9. In an ore concentrator the combination with a plurality of tables mounted one above another, of a water supply, a plurality of branch pipes having independent connections to the main and extending vertically adjacent one side of the tables, a valve in each connection for controlling the flow of water from the main into said branch, a plurality of water discharge means connected to each branch for discharging water upon each deck at selected points, a revoluble cam shaft operatively connected to the valves for operating them

successively, and means to rotate the cam shaft at predetermined intervals of time comprising a gear loosely mounted on the shaft, means to continuously rotate the gear, a clutch to connect the gear to the shaft, a spring tension lever pivotally connected to one member of the clutch for moving said member into connection with the gear, means on the gear for disconnecting the clutch member from the gear at selected points of time, means to lock the clutch member in the open position and a continuously revoluble cam having operative connections with the locking means for releasing the same at selected points of time.

10. In an ore concentrator the combination with a plurality of decks, of a main for supplying wash water to all the decks, a plurality of manifolds connected to the main, each manifold having means for discharging water onto each deck at a selected point, means independently operative to control the flow of water from the main into each manifold and means to operate the latter means in succession comprising a shaft having cams thereon, one of each being operatively connected to one of the said controlling means, a gear loosely mounted on the shaft, a clutch slidably mounted on the shaft, a lever pivoted to the clutch, a spring secured to the lever for engaging the clutch and the gear, means on the gear for disengaging the clutch at a predetermined point of time, a locking bar adapted to engage the slidable clutch when disengaged from the gear, a lever operatively connected to the locking bar for releasing the same from the clutch and a revoluble cam to actuate the latter lever at a predetermined point of time.

11. In an ore concentrator the combination with a plurality of fixed inclined tables, means to supply material to be treated to the tables simultaneously, a plurality of water distributers above each table and adapted to discharge wash water onto the surface of said tables at longitudinally separated points, a water supply main connected to the water distributers and means to control the flow of water into the distributers whereby wash water is discharged onto each table simultaneously and in order of succession of the distributers.

In witness whereof I hereunto subscribe my name in the presence of two witnesses.

PETER STENGER.
